CLAIM

The ornamental design for a perpendicular blade aviation snips, as shown and described.

DESCRIPTION

FIG. 1 is a front perspective view of a perpendicular blade aviation snips showing my new design.

FIG. 2 is a rear perspective view thereof.

FIG. 3 is a left side elevation view thereof.

FIG. 4 is a front elevation view thereof.

FIG. 5 is a right side elevation view thereof.

FIG. 6 is a rear elevation view thereof.

FIG. 7 is a top view thereof.

FIG. 8 is a bottom view thereof.

FIG. 9 is a front perspective view of an alternative embodiment of the invention, the only difference in the second embodiment being that it is a mirror image of the embodiment of FIGS. 1–8; and,

FIG. 10 is a left side elevation view of the embodiment of FIG. 9.
